UNITED STATES PATENT OFFICE.

JAMES H. DIX, OF PLYMOUTH TOWNSHIP, MONTGOMERY COUNTY, PENNSYLVANIA.

COLLAR.

1,252,791.

Specification of Letters Patent. Patented Jan. 3, 1918.

Application filed November 5, 1915. Serial No. 59,864.

To all whom it may concern:

Be it known that I, JAMES H. DIX, a citizen of the United States, and a resident of Plymouth township, in the county of Montgomery and State of Pennsylvania, have invented certain new and useful Improvements in Collars, of which the following is a specification.

My invention relates to detachable collars. The present day collar, whether of the stand-up or turned-down variety, is ordinarily provided with a rear buttonhole, adapted to register with a similar hole of the neck band of the shirt, for the purpose of projecting a collar button to join the collar with the band. The above method is objectionable not only on account of the cost of making the button holes, but also because the head of the button interferes with the free movement of the band portion of the necktie, and if the necktie band happens to slip off the head, it becomes either jammed between the folds of the turned down collar or slips off the stand-up collar.

The chief object of my invention is to slit a collar in such manner as to produce a depending extension adapted to prevent the rising of the necktie band without interfering with the movement thereof when the tie is being adjusted, and a rising extension adapted for insertion between the inner and outer ply of the neckband of the shirt.

With the above and related objects in view, my invention comprises the herein-after described new article as illustrated in the accompanying drawing, and embraced within the scope of the appended claim.

In the said drawing:—Figure 1 is a perspective view of my improved collar of the stand up variety; Fig. 2 is a similar view of my improved turned-down collar; Fig. 3 is a fragmentary section of the collar shown in Fig. 1 connected with the neckband of a shirt, and Fig. 4 is a rear view thereof in connection with a necktie.

Referring more particularly to the drawing for a detail description of my invention:—Each corresponding portion of the collars represented by 5 and 6 is provided,

midway between the button-holed portions 7 and at a distance from the lower edge 8 adapted to be in alignment with the lower edge of the neck band 9 of a shirt 10, with a downwardly projecting portion 12, and an upwardly projecting scalloped portion 13, said projections being integral parts of the collar and are formed by slitting the collar as shown. To prevent the opposite edges from catching as well as from raveling about the slit, the slit portion is preferably machine stitched, 16 representing the stitching.

When a starched and ironed collar of the above description is to be used, the scalloped portion may be slightly forced inwardly 65 and the portion 12 outwardly. The scalloped portion is then adapted for insertion under the outer ply 18 of the neck band 9, and the band portion of the necktie 20 may be inserted or passed under the depending 70 portion. The collar may then be buttoned unto the neck band in front of the shirt, and the necktie properly adjusted the depending portion permitting of the free movement of the necktie while preventing it 75 from rising.

Having thus described my improved collar and the method of effecting it, what I claim and desire to protect by Letters Patent, is—

A collar having a wave like slit midway between its ends and at the lower or neckband portion thereof, said slit forming a downwardly projecting portion of the collar adapted to pass outwardly of the necktie 85 and an upwardly projecting portion provided with scallops on opposite sides of and adjacent the depending portion and adapted for insertion under the outer ply of the neck-band of the shirt. 90

In testimony whereof I have signed this specification in the presence of two subscribing witnesses.

JAMES H. DIX.
